UNITED STATES PATENT OFFICE

EDWARD ARTHUR ROBINSON, OF MONTREAL, QUEBEC, CANADA, ASSIGNOR TO
JOSEPH ROBINSON, OF NEW YORK, N. Y.

BRACKET FOR CONNECTER HEADS

Application filed May 31, 1930, Serial No. 457,943. Renewed August 10, 1932.

My invention relates to a bracket for train pipe connecters.

A purpose of my invention is to vertically support the spaced arms of a train pipe connector on horizontal laterally spaced co-axial pivot members that extend inwardly toward one another from laterally spaced downwardly extending arms of a bracket fastened to the train.

10 A further purpose is to provide a bracket having laterally spaced downwardly extending arms that present inwardly directed pivot projections for vertically supporting the arms of a connector and in an alinement parallel therewith, outwardly spaced therefrom and preferably also spaced somewhat forwardly thereof to present a pivot support to the inner end or ends of rearwardly extending tie bolts that support spring means for 15 pressing the connector forwardly.

A further purpose is to make the bracket for a train pipe connector in the general form of a capital **H**, fastening the bracket to the train at the upper ends of the vertical members of the **H**, slidably supporting the connector upon alined inward pivot projections from the vertical members near the lower ends thereof and pivotally connecting the rearwardly extending tie bolts to such vertical members and supporting on such tie bolts suitable spring means for pressing the connector forwardly.

Further purposes will appear in the specification and in the claims.

35 I have elected to show one main form only of my invention, showing however a minor modification and selecting a main form and modified form that are practical and efficient in operation and which well illustrate the 40 principles involved.

Figure 1 is a side elevation illustrating bracket structure embodying one form of my invention and supporting one form of connector.

45 Figure 2 is a fragmentary horizontal section taken upon the line 2—2 of Figure 1.

Figure 2a is a view corresponding generally to Figure 2 but showing a somewhat different form.

50 Figure 3 is a vertical section taken upon the

line 5—5 of Figure 5 but omitting connector structure shown in Figure 2.

Figures 4 and 5 are rear and front elevations of the bracket shown in Figures 1 to 3.

Figure 6 is a side elevation of structure 55 shown in Figures 4 and 5.

Like numerals refer to like parts in all figures.

Describing in illustration and not in limitation and referring to the drawings:— 60

My bracket, as best seen in Figures 4 to 6, comprises a casting 10, preferably integral and having a general form of a capital **H**.

The upper ends of the upper vertical arms or members are bifurcated and vertically slit 65 so as to present upwardly directed flanges 11 and 12 to downwardly directed flanges, not shown, of the train structure, the slits at 13 and 14 providing a resilience in the clamping engagement with the train structure. 70

The lower arms or members 15 and 16 of the **H** are given an eye and pivot formation, the arms being perforated at 17 and 18 in a direction parallel to the length of the car above and below pivot portions 19 and 20 for 75 holding the hook ends of tie bolts 21.

The pivots 19 and 20 are preferably of least diameter in the middle, flaring toward their opposite ends where they connect, preferably integrally, with the body of the 80 bracket, thus insuring greater strength for the pivots and definite lateral positioning of the hook ends of the tie bolts.

In alinement parallel to that of the pivots 19 and 20 for the tie bolts and preferably 85 somewhat rearwardly thereof I provide inward pivot projections 22 and 23 for vertically supporting the laterally spaced arms 24 and 25 of a connector 26.

The body of the bracket has a section comprising relatively perpendicular webs 27 and 28 that are respectively lateral and longitudinal of the train, making the bracket as a whole strong and light. 90

The inner sides of the downwardly extending arms are adequately rounded at 29 to permit angular play of the connector arms to accommodate the change in alinement of the cars during travel. 95

While my invention is adapted to use with 100

different forms of connector I have illustrated it with a connector having forwardly directed hook arms, 24 and 25 that engage the upper and lower sides of the pivot projections 22 and 23 respectively.

Rearwardly of the hook arms I have provided a cross plate 30 which connects the arms together and extends laterally outwardly across the forward ends of the springs 31 and 32 that are compressed between the rearward ends of the tie bolts 21 and the rearward face of the cross plate 30.

In Figures 1 and 2 the connector 26 is indicated engaging a cooperating connector 26' of another car, the connector having been pressed somewhat rearwardly by its engagement with its fellow connector so that the plate 30 is spaced somewhat rearward from the pivots 22 and 23.

The connector is thus adapted to slide rearwardly and forwardly on the inward pivot projections 22 and 23, during this movement being continuously pressed forward by the compressed springs 31 and 32 and are adapted to angular movement while rearwardly deflected in either horizontal or vertical direction, the inwardly directed surfaces 29 of the bracket being curved to accommodate the desired universal play of the connector.

Figure 2 shows the connector in two positions, the full line position being that at which the connector is in alignment with the car and the dot-and-dash position representing the connector at an angle with the car as incident to the connecting cars being out of alignment.

In the structure of Figures 1 and 2 the hook tie bolts 21 extend rearwardly from the pivots 19 and 20 through outwardly directed slots 33 in the cross plate 30 to which the connector arms are rigidly connected.

The rearwardly directed face of the plate receives the forward ends of the springs 31 and 32, one spring for each tie bolt, the springs surrounding the tie bolts and presenting their rearward ends against forwardly directed faces 34 of nuts 35 upon the rearward ends of the tie bolts.

I show the nuts 35 provided with internal sockets 36 adapted to receive a suitable wrench or tool for loosening or tightening the nuts, also with the forwardly directed shoulders 34 to receive the outer ends of the springs and forward extensions 37 within the rearward ends of the springs for definitely positioning the rearward ends of the spring with respect to the nuts.

In the modified form shown in Figure 2a, I use one large central spring 38 instead of the smaller springs that surround the tie bolts.

The spring 38 is wholly intermediate the tie bolts and may desirably have a consider-

ably larger diameter than the springs of Figures 1 and 2.

The tie bolts support a transverse plate or abutment 39 which is provided with a forwardly directed seat at 40 adapted to definitely position the rearward end of the spring.

The brackets of the two forms may be identical but the cross plate connection 30' between the arms of the connector of the second form may be desirably smaller than the plate 30 in the first form and in both forms the cross plate should be provided with lugs 41 or 41' adapted to properly position the springs or spring.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. A bracket, laterally spaced downward extensions thereon, inwardly directed horizontal pivot projections from the extensions relatively alined and adapted to give pivot support to a train pipe connector arranged between said extensions of the bracket, a rearwardly extending tie bolt from each extension pivotally connected therewith and spring means rearwardly supported by the rear end of the tie bolts for pressing the connector resiliently forwardly.

2. A bracket for a train pipe connector having the general form of a capital H, means on the upper end of each of the upper vertical members of the H for fastening the same to a train structure, the lower vertical members below the cross of the H being adapted to span a train pipe connector, inward horizontal alined pivot projections from the lower vertical members below the cross of the H giving pivot support to said connector, and each lower vertical member having a pivot which is pivotally engaged by a rearwardly extending tie bolt.

3. In a train pipe connector, a connector head having rearwardly extending arms, a cross connection between the arms at the rearward ends thereof, each of said arms presenting vertically spaced forwardly and rearwardly extending surfaces, a bracket, laterally spaced downwardly extending members on the bracket spanning the connector arms, inward pivot projections on said members for giving the connector arms vertical support between said members and along said surfaces, a tie bolt extending rearwardly from each of the bracket members, a pivot connection between each member and tie bolt and

spring means forwardly engaging said cross connection and supported from rearward expansion by the tie bolts.

4. In a train pipe connector, a connector head having rearwardly extending arms, a cross connection between the arms at the rearward ends thereof, each of said arms presenting vertically spaced forwardly and rearwardly extending surfaces, a bracket extending downwardly from a train, laterally spaced downwardly extending arms on the bracket spanning the connector arms, inward pivot projections on the arms of the bracket for giving the connector arms vertical support between the arms of the bracket and along said surfaces, a tie bolt extending rearwardly from each of the bracket arms and pivotally connected therewith and a compressed spiral spring surrounding each tie bolt, forwardly engaging the said cross connection and supported from rearward expansion by the tie bolt.

5. A bracket for supporting a train pipe connector, said bracket having laterally spaced downwardly extending arms, a horizontally arranged inwardly extending pivot on each of said arms, said pivots being spaced apart and arranged in horizontal alignment, and each of said arms having a pivotal connection for a tie rod.

6. In combination, a bracket having laterally spaced downwardly extending arms, a horizontally arranged inwardly extending pivot on each of said arms, a connector head, a support for said head extending rearwardly past said bracket and between said arms, said support being slidably and pivotally mounted on said pivots, a tie rod pivotally engaging each of said arms and extending rearwardly thereof, and spring means supported by said tie rods and acting against said head support to press the same forwardly relative to the bracket.

7. In combination, a bracket having laterally spaced arms adjacent its lower end, a horizontally arranged inwardly extending pivot on each of said arms, a connector head, a support for said head extending rearwardly between said arms and having a transverse portion arranged to contact with said bracket, said support being slidably and pivotally mounted on said pivots, a coiled spring positioned at the rear of the bracket and having its front end arranged to press said transverse portion of the head support toward the bracket, and means pivotally connected to the bracket for supporting the rear end of the spring.

8. In combination, a bracket having laterally spaced arms adjacent its lower end, a horizontally arranged inwardly extending pivot on each of said arms, a connector head, a support for said head extending rearwardly between said arms and having a transverse portion arranged to contact with said bracket,

et, said support being slidably and pivotally mounted on said pivots, a tie rod pivotally connected to each of said arms and extending rearwardly thereof past said transverse portion on the head supporting member, and a coiled spring carried by each of said tie rods and bearing at its front end against said transverse portion.

9. In combination, a bracket having laterally spaced arms adjacent its lower end, a horizontally arranged inwardly extending pivot on each of said arms, a connector head, a support for said head extending rearwardly between said arms and having a transverse portion arranged to contact with said bracket, said support being slidably and pivotally mounted on said pivots, a tie rod pivotally connected to each of said arms and extending rearwardly thereof past said transverse portion on the head supporting member, an abutment carried by said tie rods, and a spring arranged between said abutment and said transverse portion of the head support for pressing the latter toward the bracket.

EDWARD ARTHUR ROBINSON.
